WITNESS:

ATTORNEY

UNITED STATES PATENT OFFICE.

FRANK McELHANEY, OF MORGANTOWN, WEST VIRGINIA.

AEROPLANE.

Application filed August 15, 1925. Serial No. 50,451.

To all whom it may concern:

Be it known that I, FRANK McELHANEY, a citizen of the United States, residing at Morgantown, in the county of Monongalia and State of West Virginia, have invented new and useful Improvements in Aeroplanes, of which the following is a specification.

The object of this invention is to provide improved means for controlling the vertical rudder of an aeroplane, for controlling the horizontal rudder, and for controlling the elevation of the machine with reference to a vertical shaft mounting the ground wheel and also mounting an additional vane or rudder.

A further object is to provide locking means for use with one of the controlling devices.

With the foregoing and other objects in view, the invention consists in the novel construction and arrangement of elements described, illustrated and claimed, it being understood that modifications may be made within the scope of the claims without departing from the spirit of the invention.

In the drawings forming part of this application:

Figure 1 is a view of the machine in side elevation.

Figure 2 is a view in elevation and longitudinal section.

Figure 3 is a section on line 3—3 of Figure 2 showing in top plan mechanism A for controlling the vertical elevation of the entire machine with reference to a rear lower ground wheel; showing at B mechanism for controlling the vertical rudders; and further illustrating at C mechanism for controlling a horizontal rudder.

Figure 4 is a side elevation of the structure of Figure 3.

Figure 5 is a section on line 5—5 of Figure 4.

Figure 6 is a view on line 6—6 of Figure 2.

Figure 7 is a section on line 7—7 of Figure 3.

Figure 8 is an enlarged detail view showing the manner of mounting three controlling levers adapted to operate the devices A, B and C of Figure 3.

Figure 9 is a section on line 9—9 of Figure 8.

Figure 10 is a detail view of the locking mechanism for the structure shown at A in Figure 8.

The upper and lower planes of the machine are designated respectively 10 and 12, vertical supporting elements being illustrated at 13, and diagonal braces at 14 and 15. A propeller 16 is carried by the shaft 17, and is adapted to be driven by a suitable motor (not shown).

Forward supporting wheels, or landing wheels, such as 20 are mounted on brackets or the like 21 and on transverse axial element 22. A rear landing wheel is designated 24, and is mounted in the fork 25 carried by the lower end of vertical shaft 20 or standard 26. Extending rearwardly from the fork 25 is a vertical rudder or vane 30, secured at the point 31, and a main vertical rudder is designated 32 and is carried by the stem 33, a portion of which is angular 75 in cross section and is slidable vertically in angular bore 34 in shaft 26. Shaft 26 is slidable vertically in boxing 35 and is provided with annular flanged devices 36, providing a rack for engagement by the teeth 80 of rotatable element 37 mounted on shaft 38. This element 37 includes radial arms 39 and 40, each carrying a cross bar such as 41 or 42 by means of which rotatable element or gear wheel 37 is controlled, the controlling wires being referred to below. Angular movement of gear wheel 37 produces the vertical movement of shaft 36 with reference to the main structure of the machine, and therefore varies the relative 90 position of landing wheel 24 with reference to the body portion.

A downwardly extending element 44 in the rear of fork 25 mounts a shoe 46 held in part by braces 47 and serving to protect 95 the vane or rudder 30.

In Figure 3 the controlling mechanism for effecting the change in elevation, just described, is designated in general by the letter A, this mechanism including cross bar 41 with which wires 49 and 50 are connected. The wires are further connected with each other at point 51, passing through apertured end portions 52 of bar 53 acting

as a spacing device. From point 51 a controlling wire 54 extends forwardly and is wound around pulley 55 on horizontal shaft 56 of Figure 8. This pulley is fixed 5 with reference to wheel 57 having teeth thereon for engagement by vertically movable bar 58 carried by lever 59 forming an important element of controlling mechanism A. Element 58 is normally held out 10 of engaging position by a spring 60, and this element 58 operates through the upper forked end of lever 59, the ends of the fork at 62 being rotatable with reference to shaft 56, and toothed wheel 57 being also rotatable 15 on shaft 56.

In order to lock wheel 57, I provide a lever 63 fulcrumed on shaft 56 and having pivotally connected therewith a bar 64 shown in Figure 10, this bar having pivotal 20 connection at 65 with dogs 66 pivoted to bar 67. The dogs 66 operate in reverse relation and both are thrown out in changing the adjustment of wheel 57.

In order to rotate shaft 26 on its vertical 25 axis and change the angular position of the vane 30 and the landing wheel 24, I mount the cross bar 70 on this shaft 26, the bar forming a part of the controlling mechanism indicated generally by the letter B. Connected 30 with bar 70 are wires 71 and 72 extending forwardly and around grooved wheel 72 mounted on sleeve 73 carried by horizontal shaft 56. Rigid with reference to the wheel is an operating lever 74 forming 35 a part of the mechanism B and this lever and the wheel are held in an adjusted position by means of bar or lock 75 pivoted at 76 on lever 74 and held in locking position by spring 77. The lower end of bar 75 engages 40 a toothed rack 77, and retains the lever 74 in an adjusted position.

A horizontal rudder is designated 80 and is rigid with reference to a horizontal shaft 81, rigidly mounting a central vertical arm 45 82, the opposite ends of which are connected by wires 83 and 84 with pulley wheel 85 loosely mounted on shaft 56. This wheel is controlled by the mechanism designated generally 50 by the letter C in Figure 8 and including lever 86 operating and retained in a manner similar to that described in connection with lever 74. It will be understood that wires 83 and 84 pass respectively over the upper and lower sides of wheel 85.

Shaft 81 mounting vertical bar 82 is also 55 connected by means of radial arms such as 88 with cords or the like 89 and 90 wound in reverse relation on shaft 91 rigidly mounting a grooved wheel 92. This wheel 60 92 carried in bearings 93 controls the cord or principal element 94 which passes over pulleys 95 and 96 in vertical stationary element 97 and is connected with the horizontal plane on the upper and lower sides thereof, 65 as shown at 98 and 99. In Figure 4 guiding

elements for certain of the wires are shown at 101 and 102, and these devices, or similar devices are employed wherever necessary. Figure 6 shows several similar guiding rollers.

70

The purpose of the various controlling devices has been fully disclosed in connection with the description of the construction, and no further reference to operation appears to be necessary.

75

Having thus described the invention, what is claimed as new, is:

1. In a device of the class described, a body portion, planes mounted thereon, propelling mechanism, a vertical shaft mounted 80 for rotatable and vertical movement, a stem rotatable with the shaft, and slidably vertical with reference thereto, rudders carried by the shaft and by the stem, and controlling means for shifting the rudders simultaneously.

2. In a device of the class described, a body portion, planes mounted thereon, propelling mechanism, a vertical shaft mounted 90 for rotatable and vertical movement, a stem rotatable with the shaft, and slidably vertical with reference thereto, rudders carried by the shaft and by the stem, controlling means for shifting the rudders simultaneously, and an additional rudder at an 95 angle with those first named.

3. In a device of the class described, a body portion, planes mounted thereon, propelling mechanism, a vertical shaft mounted 100 for rotatable and vertical movement, a landing wheel mounted on the shaft, a vertically disposed rudder rotated by the shaft, controlling means for the rudder, a second rudder at an angle with that first named, means controlling the second rudder, and means 105 controlling the vertical position of the shaft.

4. In a device of the class described, a body portion, planes mounted thereon, propelling mechanism, a vertical shaft mounted 110 for rotatable and vertical movement, a landing wheel mounted on the shaft, a vertically disposed rudder rotated by the shaft, controlling means for the rudder, a second rudder at an angle with that first named, means 115 controlling the second rudder, means controlling the vertical position of the shaft, a vertical stem with reference to which the shaft is movable vertically, the stem and shaft being rotatable together, and a rudder carried by the stem.

120

5. In rudder mechanism for aeroplanes, a vertically mounted shaft, means for rotating the shaft, a rudder operated by the shaft, engaging devices on the shaft, a toothed element meshing with the engaging 125 devices for elevating the shaft, means for rotating this element, and landing means carried by the shaft.

125

6. In rudder mechanism for aeroplanes, a vertically mounted shaft, means for ro- 130

- tating the shaft, a rudder operated by the shaft, engaging devices on the shaft, a toothed element meshing with the engaging devices for elevating the shaft, means for 5 rotating this element, landing means carried by the shaft, and devices for locking the means last named.
7. In rudder mechanism for aeroplanes, a vertically mounted shaft, means for 10 rotating the shaft, a rudder operated by the shaft, engaging devices on the shaft, a toothed element meshing with the engaging devices for elevating the shaft, means for rotating this element, landing means carried 15 by the shaft, and a second rudder moved by the shaft, the rudders being positioned in a vertical plane.
8. In rudder mechanism for aeroplanes, a vertically mounted shaft, means for rotating the shaft, rudders operated by the shaft, engaging devices on the shaft, a toothed element meshing with the engaging devices 20 for elevating the shaft, means for rotating this element, landing means carried by the
- shaft, and a rudder movable about a horizontal axis between the rudders first named.
9. In rudder mechanism for aeroplanes, a vertically mounted shaft, means for rotating the shaft, rudders operated by the shaft, engaging devices on the shaft, a 25 toothed element meshing with the engaging devices for elevating the shaft, means for rotating this element, landing means carried by the shaft, a rudder movable about a horizontal axis between the rudders first named, 30 operating devices connected with the forward and rear ends of the rudder movable about a horizontal axis.
10. In rudder mechanism for aeroplanes, a vertically mounted shaft, means for rotating the shaft, a rudder operated by the shaft, annular engaging devices on the shaft, a device having a segmental toothed portion 35 engaging the annular devices on the shaft, means for rotating the device last named, 40 and landing means carried by the shaft.

In testimony whereof I affix my signature.
FRANK McELHANEY.
